UNITED STATES PATENT OFFICE.

PAUL WALCKER, OF FRANKFORT-ON-THE-ODER, GERMANY.

ORGAN.

Application filed July 3, 1922, Serial No. 572,656, and in Germany July 6, 1921.

This invention relates to organs and more particularly to means for controlling the individual tones and registers or stops. An object of the invention is to produce an organ which is simple in operation and whose individual notes and stops are all controlled by devices of a practically similar type. This object is accomplished by arranging the means for controlling the 10 notes or tones and the stops in such a manner that each of the electric circuits used for any of the various controlling functions has only a single contact whose members are operated mechanically. Associated with 15 each circuit is a simple device which admits or cuts off compressed air from a common wind chest to the pipes. This device consists of a valve lever fulcrumed at the middle and provided on both ends with bellows which, when supplied with, or deprived of, air open or close the passage to the pipes. Air is admitted or let out of the bellows through intersecting channels or conduits which may be arranged at the bottom 20 or top of the wind chest, each of the said conduits being opened and closed by a double-acting electrically controlled valve in practically the same manner. In accordance with the invention this valve consists 25 of two reciprocating disks or closing members one of which is connected with the bellows which may be supplied with or deprived of, air at will. Compressed air is admitted and taken from the bellows by 30 means of a further double valve with the aid of an electrical device which is operated either by turning the electric current on or off. The electric current is controlled by a single contact with movable members. 35 By arrangements of this kind similar controlling means are enabled to be employed both for preparing the operation or playing of the organ by means of the electrical stop contacts and for the actual playing of 40 the individual notes.

To enable each of the controlling functions to be performed by means of a single contact, special devices are required which have to be arranged differently for the stops 45 and the individual notes in accordance with known methods. According to the invention this is accomplished by employing for the control of the notes an adjustable movable contact member which co-operates with another movable contact member. The second movable contact is preferably used for

the aforementioned preparatory operation. In the stop controlling device the one contact member is movable, while the other is fixed. The movable member is operated 60 by a lever which can be worked by the organ player's helpers and its arrangement is preferably such that its motions can be observed by the player at the key board. If a crescendo is required a corresponding second 65 lever is provided which acts upon the same contact.

To enable a non-rubbing or pressure contact of the kind contemplated by the invention to be used sparkless operation is 70 imperative and in accordance with this invention this is accomplished by arranging the various functions to be each performed by a magnet which consumes only about one watt, the inductance of the magnet being so small that a non-inductive resistance bridged across the contact will be sure to prevent 75 sparking. In cases in which a considerable amount of work has to be performed the employment of one watt magnets is rendered 80 possible by using several of them and closing the circuit of each by means of relay contacts each of which is also operated by a magnet of the said type. The whole arrangement in accordance with the invention 85 is adapted for all kinds of current such as continuous and alternating high or low voltage currents. In the case of a low voltage supply circuit the magnets are operated in parallel, the voltage required being about 90 10 volts. If supply circuits of higher voltages are employed the magnets are connected in series, the individual magnets responding to a drop of potential of about 1 95 volt. The coils of the magnets must of course be adapted to this drop of potential.

The invention is illustrated by way of example in the drawing in which—

Fig. 1 is a section through a wind chest in the plane of the conduits and their associated valves for the individual tone, this figure also diagrammatically illustrating the controlling devices for the tones.

Figs. 2 and 3 illustrate circuits for controlling individual tones.

Fig. 4 is a detail of Fig. 1 on a larger scale.

Fig. 5 is a cross section on the line 5—5 of Fig. 1 and a section through a device for actuating a stop or register controlling contact.

Referring to the drawing a^1 , a^2 and a^3

are pipes whose valves project into small air distribution chambers b^1 , b^2 , b^3 located in the top cover of the wind chest. The pipes belonging to the various stops or registers are supplied with air from the said distribution chambers into which air is admitted through passages c^1 , c^2 , c^3 that can be closed by hinged valves d^1 , d^2 , d^{31} , d^{32} . Each hinged valve has two bellows one on each side of its fulcrum q^1 . These bellows are operated by compressed air admitted into, or allowed to escape from, the conduits f^1 , g^1 , g^2 , f^2 , f^{31} , f^{32} , g^{31} , g^{32} . The conduits g^1 , g^2 , g^{31} are all connected to a passage g which can be made to communicate with the compressed air chamber h^1 or cut off from this chamber and simultaneously connected with the atmosphere. The manner in which the passage g is connected to or disconnected from the chamber h^1 and the atmosphere will be explained hereinafter. The channel g^{32} is connected to a channel which is similar to the channel g and by this means the pipes a^3 can be affected by wind admitted from two different directions.

The conduit f^2 has air admitted into, or cut off from, it in a similar manner to the channel g as shown in Fig. 5. The conduits f^1 , f^{31} , f^{32} , etc. have air admitted to, or cut off from, them by valves which are individual to these conduits.

As shown in Fig. 1 the air in the channel g is controlled with the aid of a solenoid i whose movable core has a head which normally closes an opening k , this opening or port k being permanently connected to the chamber h^1 of the wind chest. When the solenoid i is energized it raises its movable core so as to open the port k whilst closing a port m which normally establishes communication with the atmosphere. By this action of the solenoid the bellows n , whose exterior is subjected to the pressure of the air in the wind chest, has compressed air admitted into it so that the closing member o is shifted to the right so as to cut off the passage g from the chamber h^1 or wind chest, while the disk p allows the channel g to communicate with the atmosphere. When compressed air is let out of the bellows n the opposite effect is accomplished.

The admission of the pressed air on both sides of the member o results that this member is moved to the right because the air acts first on the disk p being in compact connection with the member o , until the member o closes the opening at its right hand surface. The opposite effect is obtained when the inside of the bellows n is out of connection with the pressed air so that the air pressure only acts from the outside of the bellows n , whereby the parts o and p are retracted to the left.

The valve with two closers or disks shown in Fig. 5 operates in a similar manner, ex-

cept, that this valve, which controls the port, is operated in an opposite sense, i. e. the port t normally, that is to say when the solenoid i^1 is not energized, is open so as to connect the interior of the bellows n^1 with the windchest h^2 . In this case, the plate u rigidly connected to the core of the solenoid under the influence of the weight of the core, rests upon the base of the casing enclosing the valve so as to hold open the hole or port t , while the upper port connecting the interior of the valve with the open air being closed by the core itself. When the solenoid is energized the core will be raised and the upper port will become open while the plate u having the same diameter as the hole or port t will enter the port and close the same.

The hinged valve d^1 , which is fulcrumed at q^1 , is acted upon by spring r^1 which maintains the valve with its left hand portion up against the opposite co-operating surface as shown, even when there is no wind in the chamber h^1 , that is to say when there is no wind in the organ. Similar springs are provided in all the other hinged valves. As illustrated in the drawing the hinged valve d^1 is acted upon by the compressed air in the channel g^1 , there being no compressed air in the conduit f^1 . When the compressed air is discharged from the conduit g^1 the hinged valve d^1 is maintained in the same position, because the left hand lever of the same is longer than its right hand lever so that the air in the chamber h^1 forces the left hand part of the valve up against its co-operating or campanion surface. When compressed air is admitted from the chamber h^1 into the conduit f^1 the valve is swung round so that its right end is raised while its left end descends, a connection being then established between the wind chest h^1 and the pipe passage c^1 through the port s^1 in the valve d^1 .

The valves d^2 and d^{32} are similar to valve d^1 . In the position of the valve d^2 shown in full lines which corresponds to the illustrated position of closing member o and disk p , the interior of the chamber h^2 is disconnected from the pipe passage c^2 . When the valve d_2 is in the position shown in dotted lines owing to the movement of parts o and p from the left to the right connection is established between the chamber h^2 and pipe channel c^2 as indicated by the arrow.

Valves d^{32} is shown as to be in such a position. The pipe a^3 (Fig. 1) may be played by air admitted through different inlets controlled by different valves as d^{31} , d^{32} . This arrangement is necessary for transmissions and when different claviers are coupled to each other, etc. The chambers h^1 , h^2 , h^3 are all in communication with each other so that they may be regarded as a common wind chest. Instead of operating valves by solenoids i magnets may be used which operate

the valves by means of hinged armatures or the like. When alternating current is employed for operating the valves the preference will generally be given to solenoids as they are better for the prevention of noises.

The construction of the valve is such as to make them suitable for mass production and to be screwed singly or as individual parts to the wind trunk. Similar types of valves 10 may be employed for operating or putting on the stops and for controlling the individual tones. Exhaust valves or normally deflated valves in accordance with Fig. 1 are preferably used for operating the individual tones, 15 while normally inflated valves are preferably employed for operating the stops, because the function initiated by the stops may lag to a certain extent behind their operation while the tones must sound immediately their control valves are operated.

Fig. 2 illustrates circuits which are suitable for operation with a low continuous current voltage of say ten volts. The magnet 1 is energized by current from a suitable current source such as a battery 2 when the contact members 3, 4 or 31, 41 are closed. The contact members 3 and 31 and also the members 4 and 41 are all movable. The members 4 and 41 may be set to certain positions by 20 preparatory adjusting operations, and the members 3 and 31 are operated when the organ is played. Such preparatory adjustments are effected when the individual tones and stops are controlled from different positions. Contacts which are closed by merely 25 pressing the members together, without any rubbing action taking place, can only be used if sparking is prevented by a suitable means such as a noninductive resistance. A spark 30 preventer 5 of this kind is shown in Fig. 2.

In Fig. 3 a contact with similar contact members 3, 4 is shown which controls two magnets 60, 61 that are switched one after the other. When the contact 3, 4 is closed the magnet 60 is energized and its armature 7 switches on the magnet 61. Here also each contact is provided with a spark preventer 50, 51. The armature 7 may be arranged to switch on not only a single magnet 61 but a series of such magnets one after the other whose individual contacts are each provided with a spark preventer. The object of this arrangement is to enable more than one magnet to be switched on or off without sparks arising at the contacts. By subdividing the circuits of the magnets in this manner it is possible to eliminate the sparking effects due to the small inductances of the various magnets by a small resistance associated with the contact of each small magnet. This arrangement is particularly applicable for controlling individual tones in big organs with divided wind trunks and having, say, more than ten stops for one manual.

When the organ is operated from an alter-

nating current supply source, so that the solenoids do not keep their cores perfectly still when energized, the arrangement preferably employed will be that shown in Fig. 5, in which the bellows n^1 are deflated when 70 the core of the solenoid is attracted. The deflation of the bellows n^1 is effected by the head u of the core of the solenoid i^1 being caused to close the bottom port t while establishing a connection between the interior of 75 the bellows n^1 and the atmosphere through the second port located above the port t .

The relay contact v which is closed by the armature 7 (Fig. 3) corresponds to a similarly designated contact in Fig. 1 which co- 80 operates with a spring contact v^1 . The spring v^1 is pressed against the common return v when the valve controlled by the solenoid i is operated.

In the lower part of Fig. 1 the manner is 85 illustrated in which, by means of a key 11 which lifts a spring valve, a lever 13 can be rocked whose right hand end carries adjustable contact members 140, 141. The right end 15 of the lever 13 is guided by a pin 16 fixed in the part 17. The downward travel 90 of the right end of the lever 13 is limited by a set screw or nut 18. Arranged beneath the adjustable contact 140, 141 are movable contact members 190, 191 in the form of 95 hinged bars, which form common returns of the individual circuits. The hinged bar 190 can be moved by a rod 20 in the direction of the arrow. The hinged common return bar 191 can be swung round by the armature 100 22 of a magnet 21. The contact members 140, 141 are annular pieces of flat metal or metal loops guided in slots in the lever 13 so as to be always held in a certain position. These flat contact members or loops 140, 141 105 are riveted to threaded stems 142, 143 whose threaded portions are screwed into sleeves 144, 145 of hard rubber.

The holes in which the sleeves 144, 145 110 are slidably arranged are closed by covers 146, 147 adapted to be fastened in the said holes. Springs 148, 149 are positioned in the holes for pressing down the sleeves. The wires connecting the parts 140, 141 with the contact member of the lever 17 are fastened to the upper ends of the stems 142, 143 and led through the covers. After taking off the covers 146, 147, the sleeves 144, 145 together with the stems may be removed 115 from the holes and the stems may be adjusted in the sleeves by screwing. Thus the contact between the parts 140 and 141 with the bars 190 and 191 may be regulated. This arrangement is particularly suitable for 120 coupling the manuals and octaves.

The part 23 is connected to the organ cable from which only one wire 24 is shown and consists of a spring 25 which is connected to the contact members 140, 141 by being pushed into its proper position. An 125

exchangeable spark preventer 26 is associated with the said contact spring. 27 is a return wire which leads from the common returns 190, 191 and the spark preventer 26 to the battery 28. 29 is the return wire from the magnets or solenoids. Two series of projections 52 and 52^a are arranged on each of the bars 37 and 37^a besides each other, one series 52 of these projections projecting at one side of the said bars the other series 52^a staggered to the first series 52 at the other side of the said bars.

The lower part of Fig. 5 illustrates a stop control device. 32 is a fixed bus bar and 33 a movable contact member or spring co-operating therewith. The spring or wire 33 is operated so as to make contact with the bus bar 32 in any suitable manner. The means illustrated for effecting this are a setting device 34, a pull 35, a rocking board 36, two further rocking boards or bars 37, 37^a, a crescendo roll or drum 38, and two hinged bars 39 and 39^a. The drum 38 has a plurality of projections or cams situated in staggered relation on the drum and from which one 54 is shown in section.

The spring 33 may be pressed down by a one-arm lever 42 pivoted at 43. The pivot 43 is fixed to a lever 44. Hence when the right end of the lever 44 is lowered the lever 42 will press down by its own weight the spring 33 to establish contact with the bus bar 32. At its left end the lever 44 is provided with an indicating pin or plate 45. By pressing down the setting member 34 which swings on the pivot 46, the left end of the lever 44 can be raised. When the lever 44 is moved in this manner the indicator 45 emerges from its hole and is preferably arranged to point to a disk 47 which displays the name of the particular stop or register in question, so that the player of the organ will see that this stop is put on. Connected with the lever 44 is a locking member or spring 48 which retains the lever in whatever position it may have been moved into. The rocking bars 37, 37^a are used for operating a number of levers 44 simultaneously, either for restoring them, or for moving them into their off-normal positions. Hence these rocking bars correspond to the fixed combinations of the organ. Screwed fast to the rocking bars 37, 37^a are small projections 52, 52^a some of which extend upwards, while the others extend downwardly. The projections 52 serve to put the stops on, while the projection 52^a operates to put them off.

Connected to the pull or knob 35 is an angle piece 53 in which are pivoted two one-armed levers 53^a, 53^b. The flat pivoted bar 36 is adapted to be turned in the direction of the arrow. When a knob 35 is pulled out, and the one-arm lever 53^a is thus drawn to the left, the rotation of the bar 36 will

result in the lever 35^a being swung upwards so as to rock the lever 44. Any levers 44 of stops which are not drawn at this time, but which may have been previously drawn are restored to their normal positions when the bar 36 is turned as described, this restoration being effected by means of the levers 53^b. The knob or pull 35 and its associated parts are used for setting up any desired combination of claviers etc.

The putting on or off of all stops is effected by means of hinged bars 39, 39^a, which engage with the right hand ends of all the levers 44^a simultaneously. The crescendo drum 38 acts upon a series of levers 44. For each stop there are two levers 44 placed side by side whose indicators 45 preferably have different colours. The drum 38 has teeth 54 each of which controls a certain stop and which operate in succession. The teeth effect the levers 44, 44^a by engaging with a pivoted dog 55 which is pressed down when the drum 38 is rotated counter-clockwise and is brushed aside when the drum is rotated in the opposite direction. The stop is returned to normal by the same tooth engaging with the oblique end of the lever 44 and thus raising it.

By providing two independent levers 44 one of which is operated by the crescendo drum the organ player is enabled to observe which stops are operated by the crescendo drum and which of them are operated by other means. The stops that have been put on by the crescendo drum or by other means can be restored by bars 56, 56^a which are adapted to be moved up and down and provided with projections arranged to act on the one or the other series of levers 42. This operation by means of the bars 56, 56^a can be effected without affecting the manual adjustments and the indicators at the front of the organ, because the arms 42 are raised without moving the levers 44. By lowering the bars 56 or 56^a the particular group of stops, i. e. the settings effected by the crescendo drum and the other devices, can be made to take effect again. In cases in which separate indicators for the crescendo drum are not required, this drum can be made to act on the same levers that are operated by the other selectable stop setting means. In such a case the crescendo stop cannot be put out of operation by itself.

I claim:—

1. In an organ, pipes, a windchest connected to a pipe by means of an opening, a closing member for closing the said opening, a tone-channel, a stop-channel, and a double armed lever associated with the said closing member and being under the influence of the action of both the tone-channel and the stop-channel.

2. In an organ, pipes, a windchest con-

nected to a pipe by means of an opening, a closing member for closing the said opening, a double armed lever associated with the said closing member, and an inflatable device on each arm of the said lever one device being connected to a tone-channel and the other to a stop-channel.

3. In an organ, pipes, a windchest connected to a pipe by means of an opening, a closing member for closing the said opening, a double armed lever associated with the closing member and being under the action of a tone-channel and a stop-channel, a first controlling means for controlling the said tone-channel, and a second controlling means for controlling the said stop-channel so as to charge or discharge the said channels.

4. In an organ, pipes, a windchest connected to a plurality of pipes by means of an opening for each pipe, a plurality of closing members each adapted to close and to open one of said openings, and a double armed lever associated with one of said closing members the lever being under the action of a tone-channel and a stop-channel.

5. In an organ, pipes, a windchest connected to a pipe by means of an opening, a doubled armed lever, a first inflatable device and a closing member for closing the said opening on one arm of the said lever, the said inflatable device being arranged on the end of the said arm while the closing member is arranged adjacent to the turning point of the said lever, and a second inflatable device on the other arm of the said lever, one of the said inflatable devices being connected with a tone-channel the other inflatable device being connected with a stop-channel.

40. 6. In an organ, a windchest, a pipe, a plurality of openings leading from the windchest to the said pipe, a closing member for each opening, and a double armed lever associated with each of said closing members, the said levers being under the action of different tone-channels and different stop-channels.

7. In an organ, a pipe, a windchest having an opening for supporting air to the said pipe, a closing member for the said opening associated to a double armed lever, one arm of the said lever being under the action of a tone-channel, the other arm under the action of a stop-channel, and a spring adapted to keep closed the said closing member.

8. In an organ, a pipe, a windchest having an opening for supporting air to the said pipe, a closing member for the said opening associated to a double armed lever, one arm of the said lever being under the action of a tone-channel, the other arm under the action of a stop-channel, and a spring adapted to keep closed the said closing member, the

said spring being arranged close to the turning point of the said lever.

9. In an organ, a windchest, a tone channel and a valve having two closing members adapted to connect the said channel with the said windchest or with the open air, the said valve being arranged in a separate casing removably fastened to the outside of the windchest.

10. In an organ, a windchest, a stop channel and a valve having two closing members adapted to connect the said channel with the said windchest or with the open air, the said valve being arranged in a separate casing removably fastened to the outside of the windchest.

11. In an organ, a windchest, a tone channel, a stop channel, a first controlling device for controlling the said tone channel, a second controlling device for controlling the said stop channel, each controlling device consisting in a valve having two closing members adapted to connect the said respective channel with the said windchest or with the open air, and an inflatable device one part of which forming itself one of the said closing members adapted to be controlled so as to be charged with the pressed air of the said windchest or discharged to the open air, each valve being arranged in a separate casing removably fastened to the outside of the said windchest.

12. In an organ, a windchest, a tone channel, a stop channel, a first controlling device for controlling the said tone channel, and a second controlling device for controlling the said stop channel, each controlling device consisting in a valve having two closing members adapted to connect the said respective channel with the windchest or with the open air each controlling valve and controlling means being arranged in a casing removably fastened to the outside of the said windchest the casings being equally formed in such a manner that each of the valves is applicable as well to a tone channel as to a stop channel of the windchest.

13. In an organ, a windchest, a controlling valve having an inflatable chamber, and a double acting controlling means for connecting the said chamber with the said windchest or the open air, the said double acting controlling means being adapted to act in one direction of movement by weight and in the other direction to be lifted by force, the said valve being arranged in a casing removably fastened to the outside of the windchest.

14. In an organ, a windchest, a controlling valve having an inflatable chamber, a double acting controlling means for connecting the said chamber with the said windchest or the open air, the said double acting controlling means being adapted to act in one direction of movement by weight and in the other di-

rection to be lifted by force, the said valve being arranged in a casing removably fastened to the outside of the windchest, and electrical means for lifting the said double 5 acting controlling means.

15. In an organ, a windchest, a controlling valve having an inflatable chamber, a double acting controlling means for connecting the said chamber with the said windchest or 10 the open air, the said double acting controlling means being adapted to act in one direction of movement by weight and in the other direction to be lifted by force, the said valve being arranged in a casing removably 15 fastened to the outside of the windchest, and a solenoid for lifting the said double acting controlling means.

16. In an organ, a windchest, a valve connecting a channel with the interior of the 15 said windchest or with the open air, an inflatable device for moving the valve, controlling means for connecting the interior of the inflatable device with the interior of the windchest or with the open air, and moving 25 means for moving the controlling means, the controlling means including a weight provided with a plate the latter being adapted to close an opening connecting the windchest with the interior of the inflatable device 30 vice under the action of its weight and to be lifted opposite to the said weight to open the said opening.

17. In an organ, a double acting pneumatic valve, a channel being in connection 35 with the inflatable part of the said valve, in the channel two openings, and a controlling member for the said openings consisting of a weight in connection with a plate, the said plate being as well adapted to be arranged 40 within the said channel as opposite to the weight at the outside of the said channel.

18. In an organ, a stop relay, means for controlling the said relay, a movable member for actuating the said controlling means, 45 a stop-key, a mechanical device for setting selectable combinations, and a mechanical device for setting fixed combinations, the said stop key and the said devices being each adapted to move the said member.

50. 19. In an organ according to claim 18, a key-board, and means for making remarkable the movement of the said member on the key-board.

55. 20. In an organ, a series of stop-relays, means for controlling each of the said stop-relays, a series of movable members each adapted to actuate one of the said controlling means, a series of stop-keys each adapted to actuate a said member, a device for 60 setting selectable combinations, and a plurality of devices for setting fixed combinations, each of the said devices being adapted to move a plurality of the said members.

65. 21. In an organ, a series of stop relays, means for controlling each of the said relays,

a series of first movable members each adapted to actuate one of the said controlling means, a series of stop keys, each of the keys being adapted to act upon a said first member, a series of second movable 70 members each adapted to actuate one of the said controlling means, and a crescendo device adapted to actuate a plurality of the said second members.

22. In an organ according to claim 21, a 75 device for setting selectable combinations adapted to actuate the said first movable members.

23. In an organ according to claim 21, a device for setting selectable combinations, 80 and a device for setting fixed combinations each adapted to actuate the said first movable members.

24. In an organ according to claim 21, a key-board, and means for independently 85 making remarkable the movement of the said first and the said second members on the key-board.

25. In an organ according to claim 21, a device for setting selectable combinations, a 90 device for setting fixed combinations, each of the said devices being adapted to actuate the said first movable members, a key-board, and means for independently making remarkable the movement of the said first and 95 the said second members on the key-board.

26. In an organ, a windchest, a valve connecting a channel with the interior of the said windchest or with the open air, an inflatable device for moving the valve, controlling means for connecting the interior of the inflatable device with the interior of the windchest or with the open air, and moving means for moving the controlling means, the controlling means including a weight 100 provided with a plate the latter being adapted to open an opening connecting the windchest with the interior of the inflatable device under the action of its weight and to be lifted opposite to the said weight to close 105 the said opening.

27. In an organ, a windchest, a first channel, a first valve adapted to connect the first channel with the interior of the windchest or with the open air, a first inflatable device 110 for moving the said valve, first controlling means for connecting the interior of the said inflatable device with the interior of the windchest or with the open air, first moving means for moving the said controlling 115 means, the said controlling means including a weight provided with a plate the latter being adapted to close a first opening connecting the windchest with the interior of the said inflatable device under the action 120 of its weight and to be lifted opposite to the said weight to open the said opening, a second channel, a second valve adapted to connect the second channel with the interior 125 of the windchest or with the open air, a 130

second inflatable device for moving the said second valve, second controlling means for connecting the interior of the said second inflatable device with the interior of the windchest or with the open air, and second moving means for moving the said second controlling means, the said second controlling means including also a weight provided with a plate, the latter being adapted to 10 open a second opening connecting the windchest with the interior of the said second inflatable device under the action of its weight and to be lifted opposite to the said weight to close the said opening, the said first controlling means and the said second controlling means being adapted to be interchanged, so as to change the first valve to act like the second valve.

28. In an organ, a windchest, a first channel, a valve adapted to connect the first channel with the interior of the windchest or with the open air, an inflatable device for moving the said valve, a second channel communicating with the interior of the said inflatable device, a first opening in the said second channel adapted to connect the windchest with the said channel, a second opening in the said second channel adapted to connect the said second channel with the open air, and a controlling means adapted to alternatively close and open one of the said openings.

29. In an organ, a windchest, a first chan-

nel, a valve adapted to connect the first channel with the interior of the windchest 35 or with the open air, an inflatable device for moving the said valve, a second channel communicating with the interior of the said inflatable device, a first opening in the said second channel adapted to connect the 40 windchest with the said channel, a second opening in the said second channel adapted to connect the said second channel with the open air, a controlling means adapted to alternatively close and open one of the said 45 openings, and moving means for moving the said controlling means, the said controlling means including a weight provided with a plate and adapted to be lifted by the said moving means, the weight with its plate 50 being adapted to be arranged so that the weight itself in its normal position closes the said second opening and in its lifted position opens it, while at the same time the said plate is adapted to open and close respectively the said first opening, the same weight being also adapted to be arranged with its plate between the said openings so that the plate is adapted under the action of the weight to open the first opening and to 55 close the second opening or vice versa to close the first opening and to open the second opening, when the weight is lifted.

In testimony whereof I affix my signature.

PAUL WALCKER.
